UNITED STATES PATENT OFFICE

132,880

DESIGN FOR A VELOCIPED

John G. Rideout, Cleveland, Ohio, assignor to
Junior Toy Corporation, Hammond, Ind., a cor-
poration of Indiana

Application March 20, 1942, Serial No. 106,262

Term of patent 7 years

To all whom it may concern:

Be it known that I, John G. Rideout, a citizen of the United States of America, residing at Cleveland, in the county of Cuyahoga and State of Ohio, have invented a new, original, and ornamental Design for a Velocipede, of which the following is a specification, reference being had therein to the accompanying drawings, forming a part thereof, wherein:

Figure 1 is a top plan view of a velocipede showing my new design, the characteristic fea-

tures of which being the portions shown in solid lines;

Figure 2 is a side elevational view thereof;
Figure 3 is a front elevational view thereof;
and

Figure 4 is a rear elevational view thereof.

I claim:

The ornamental design for a velocipede, sub-
stantially as shown and described.

JOHN G. RIDEOUT.
